UNITED STATES PATENT OFFICE.

CHARLES A. BRONAUGH AND SAMUEL L. KISTLER, OF LOS ANGELES,
CALIFORNIA.

WHIP-SNAPPER ATTACHMENT.

No. 800,066.

Specification of Letters Patent.

Patented Sept. 19, 1905.

Application filed August 14, 1901. Serial No. 72,084.

To all whom it may concern:

Be it known that we, CHARLES A. BRONAUGH and SAMUEL L. KISTLER, citizens of the United States, residing at Los Angeles, county of Los Angeles, State of California, have invented new and useful Improvements in Whip-Snapper Attachments, of which the following is a specification.

Our invention relates to an improvement in whip-snapper attachments, and has for its object a ready means of applying a snapper without the use of tools or special skill, it being our purpose to bring it within the province of the user to apply a snap without the necessity of employing one skilled in the art to do the work; and it consists in a ferrule adapted to be secured to the whip in any approved manner, said ferrule provided with an orifice in the top in connection with a loop which extends through the orifice and is held thereby, affording means for the attachment of the snap.

In the accompanying drawings, Figure 1 is a view of the upper end of a whip, showing the snap applied; and Fig. 2 is an enlarged view, partly in section, showing a manner of fastening the loop in the ferrule.

A represents the whip, and B is a ferrule, preferably having the inwardly and upwardly

struck barbs B', adapted to hold the ferrule 30 on the broken end C of the whip. The upper end of the ferrule has a hole D, and through this hole the loop E extends. This loop is preferably made of flexible material, such as cord, having its ends tied together in a knot to 35 prevent its withdrawal through hole D in the ferrule, which it approximately fits.

The snap F is secured to the loop in the usual manner of attaching snaps to whips.

Having fully described our invention, what 40 we claim as new, and desire to secure by Letters Patent, is—

A whip-snapper attachment comprising a ferrule adapted to be secured to a whip-stock and having an opening at its upper end, and 45 a loop composed of flexible material inserted in the opening in the ferrule, the ends of the loop united to form a knot, said loop adapted to receive the snapper.

In witness that we claim the foregoing we 50 have hereunto subscribed our names this 7th day of August, 1901.

CHAS. A. BRONAUGH.
SAMUEL L. KISTLER.
